TO HARRY D. HEDISON, DOING BUSINESS AS HEDISON MFG. CO., OF PROVIDENCE,
RHODE ISLAND.

SEPARABLE CUFF BUTTON.

Application filed July 15, 1925. Serial No. 43,739.

To all whom it may concern:

Be it known that we, WALTER E. FIELD and FRED C. STOWE, citizens of the United States, residing at Providence, in the county 5 of Providence and State of Rhode Island, have invented certain new and useful Improvements in Separable Cuff Buttons, of which the following is a specification.

This invention relates to an improved construction of cuff button of the separable type, and has for its object to provide a button of this character having two members separably connected together, each having inner and outer heads, a latch or lock member being provided in one of the button parts to releasably engage the other button parts, which lock may be actuated by an axially movable post operable through the outer head of one of the members to release 20 the button parts.

A further object of the invention is to form the two separate button parts as stud and socket members, the stud member being provided with a hollow projection fitting 25 into a recess in the socket member and a latch in the socket member extending into position to engage parts of the stud member and an axially movable push piece in the stud member normally in disengaged position and adapted to be operated to contract 30 the latch to release the button parts.

With these and other objects in view, the invention consists of certain novel features of construction, as will be more fully 35 described, and particularly pointed out in the appended claims.

In the accompanying drawings:

Figure 1 is a sectional side elevation illustrating one form of this improved button 40 construction with the two parts connected.

Figure 2 is a section on line 2—2 of Figure 1, looking in the direction of the arrows.

Figure 3 is a sectional detail of the tubular push piece.

Figure 4 is a perspective view of the spring latch member.

Figure 5 is a sectional side elevation of the end plate of the stud member showing the central guide protuberance formed 50 thereon.

Figure 6 is a face view of the under side of the end plate of the socket member showing the latch-guiding slot therein.

Figure 7 is a sectional side elevation illus-

trating the push members as pressed inwardly to move the latch to disengaged position.

Figure 8 shows the button parts separated.

Figure 9 is a modification illustrating the latch as carried by the stud member of 60 the button, and the releasing push piece by the socket member thereof.

It is found that a practical construction of separable button may be provided in which the locking or latch member may be 65 carried in one of the button parts and the operating push piece in the other of the button parts and that these latch members may be arranged to extend into position to engage and releasably secure together the 70 opposite parts of the button, whereby an axial movement of the push piece will contract these latch members permitting the button parts to separate; and the following 75 is a detailed description of the present embodiment of this invention showing one construction by which these advantageous results may be accomplished:—

With reference to the drawings, 10 designates the stud member and 11 the socket 80 member of our improved separable button, the socket member being provided with an outer head 12 and an inner head 13. This inner head is provided with an end plate 14 having a central socket or recess 15 for the 85 reception of the projection or protuberance of the stud member, and this plate is preferably formed concaved on its outer surface for the purpose of guiding this protuberance into the socket or recess therein to 90 facilitate connecting the button parts. The bottom of this socket is slotted transversely as at 16 through which the ends of the latch member 17 extend and are guided. These latch ends 18 are provided with engaging 95 shoulders 19, the heads being pressed normally outwardly by action of the spring arms 20. These arms are connected by a bridge 21 which is provided with an outwardly extending riveting lug 22 which is 100 adapted to extend through the opening 23 in the plate 24 and riveted therein for the purpose of supporting this latch in operative position in its button member.

The stud member of this button is provided with an outer head 25 and an inner head 26, the inner head being provided with an end plate 27 drawn or swaged, as best

shown in Figure 5, to provide a hollow protuberance 28, in the bottom wall of which is formed a circular opening 29 for the reception of the latch members, and which 5 protuberance is adapted to extend into the recess 15 of the socket member.

In order to move the engaging ends 18 of the latch inwardly toward each other to contracted or released position, we have provided a tubular push piece 30, the lower end of which just enters and is guided in the recess or socket formed by the hollow protuberance 28, the lower edge of this tube being preferably counterbored or beveled as 15 at 31 to engage the inclined ends of the latch to force them toward each other against the spring of their arms, and the outer end of this tube is preferably flaring as at 32 providing a shoulder against which the operating spring 23 normally presses to hold the tube in its outward position and also serves to hold the flange 34 of the push button 35 normally up against the inner surface of the outer button head. By this improved construction when it is desired, the two button 25 members or parts may be readily connected by simply pressing them together which will cause the latch 17 in the socket member to snap into engagement with the walls of the stud member and when it is desired to release these parts it is only necessary to press the button end 35 inwardly, as best illustrated in Figure 7, causing the push piece 30 to contract the latch members, which will 30 permit the button parts to be readily separated.

In some instances, instead of mounting the latch members in the socket member of the button, we may reverse this construction and 40 mount the latch in the stud member of the button, and the push piece in the socket member thereof, by which construction the parts will work substantially the same and appear substantially as illustrated in the modified construction shown in Figure 9.

The foregoing description is directed solely towards the construction illustrated but we desire it to be understood that we reserve the privilege of resorting to all the 50 mechanical changes to which the device is susceptible, the invention being defined and limited only by the terms of the appended claims.

We claim:

55 1. A separable cuff button comprising two button parts, each having inner and outer heads, a latch member in one button parts arranged to snap laterally into engagement with portions of the other button part, an axially movable latch-engaging push member in the other of said button parts, one of said members having a surface inclined to the axis and in engagement with the other of said members, whereby an axial 60 movement of the push member causes a

lateral releasing movement of the latch member to permit the separation of the button parts.

2. A separable cuff button comprising two button parts, each having inner and outer heads, a spring latch in one button part arranged to snap laterally into engagement with portions of the inner head of the other button part, the end portion of said latch being set on an incline to the button axis, and an axially movable latch engaging push piece in the other of said button parts having an opening in its end of a size to engage said inclined end portion to act upon and withdraw said latch from engaged position upon an axial movement of said push piece to permit separation of the button parts.

3. A separable cuff button comprising stud and socket members, each having inner and outer heads, a protuberance on the stud member, a recess in the socket member to receive said protuberance, oppositely disposed latch arms guided in a slot in one of said button members and arranged to releasably engage parts of the other member, and an axially-movable tubular push piece in the other of said button members arranged to set over the ends of said latch arms to force the same inwardly to release said button members and simultaneously expel the stud from its socket member.

4. A separable cuff button comprising stud and socket members, each having inner and outer heads, an integral protuberance on the inner head of the stud member, a recess in the inner head of the socket member to receive said protuberance, a latch in said recess to engage and grip the walls of said protuberance upon entering the same, and an axially movable push piece in the stud member for moving said latch to release the button members and expel the stud from its socket.

5. A separable cuff button comprising stud and socket members, each having inner and outer heads, an open ended integral protuberance on the stud member, a recess in the socket member to receive said protuberance, a latch member having a pair of spring arms supported in the body of the socket member and having enlarged end portions extending into said recess and through the opening in said protuberance to engage the walls thereof when the protuberance is positioned in said recess, and an axially movable push piece in the stud member having an opening in its end to fit over and contract said latch arms by an axial inward movement to disengage said button members.

6. A separable cuff button comprising stud and socket members, each having inner and outer heads, an integral protuberance on the stud member, a recess in the socket member to receive said protuberance, a latch member having a pair of spring arms sup-

ported in and extending into said recess into position to engage the walls of said protuberance when positioned in said recess, a push button in the outer head of the stud 5 member, and a push piece under outward spring pressure to receive axial operating movement through said button, the inner end of said push piece being guided in said protuberance and shaped to engage and contract said latch arms to disengage the same 10 from the walls of said protuberance and expel the stud from its socket member.

In testimony whereof we affix our signatures.
